ENGINE BRAKE

Bernard Ucko, North Plainfield, N. J., assignor
to International Motor Company, New York,
N. Y., a corporation of Delaware

Application March 9, 1931, Serial No. 521,144

9 Claims. (Cl. 123—90)

The present invention relates to engine brakes and embodies, more specifically, an improved form of brake, wherein the engine is converted into a true two cycle air compressor, thus effectively braking the same.

More particularly, the invention embodies an improved braking mechanism for internal combustion engines which is readily applicable to standard makes and types of engines without modifying the construction thereof or altering, materially, the auxiliary elements thereof. The mechanism by means of which the braking is accomplished embodies a hydraulic structure which is adapted to act upon the exhaust valve mechanism of the engine to open the exhaust valves during each down stroke of the respective pistons. The mechanism is actuated by the rocker arm shaft turning mechanism in such fashion as to cause the exhaust valve opening mechanism to function when the rocker arm valve actuating mechanism is rendered inoperative, thus causing air to be drawn into the cylinders upon the down strokes of the respective pistons and compressed upon the up strokes.

An object of the invention is to provide an engine brake design which does not add to the length of the engine.

A further object of the invention is to provide an engine brake design which is simple in construction and operation and the parts of which may be added to any engine structure without modifying the engine design or materially altering the auxiliary elements thereof.

A further object of the invention is to provide a device of the above character, wherein the conventional valve mechanism is utilized as the engine brake mechanism when it is desired that the engine operate as a brake.

A further object of the invention is to provide a rigid and quiet drive, this object being attained by the utilizing of mechanism which does not require the shifting of the cam shaft, a further object of the invention being to provide a structure, wherein the brake elements are independent of the engine and thus do not impair the normal operation of the engine upon failure of such elements.

Further objects, not specifically enumerated above, will be apparent as the invention is described in greater detail in connection with the accompanying drawing, wherein the single figure of the drawing is a view in section taken through a cylinder head and valve actuating mechanism of a standard form of engine, the engine brake structure of the present invention being shown as

installed thereon and operating in conjunction therewith.

Referring to the above drawing, an engine cylinder head is shown at 10 as provided with an exhaust passage 11 and an exhaust port 12. Exhaust valve 13 is mounted upon a valve stem 15 mounted in the head and a collar 16 seats a valve spring 17 to maintain the valve normally closed.

Rocker arm shaft 18 is mounted upon eccentrics 19 and is thus shifted eccentrically of the axis of the eccentrics by means of a shifting lever 20. Rocker arms 21 are carried by the shaft 18 and are formed with heads 22 which engage the top of valve stems 14.

Upon the other end of the rocker arms, adjustable tappets 23 are mounted, these tappets being engaged by cups 24 upon push rods 25. Lost motion springs 26 are provided between the rocker arms and the respective push rods 25, and inlet 20 and exhaust cams 27 on cam shaft 28 engage the pads 29 of the respective rods 25.

The foregoing mechanism is of standard form and typical of internal combustion engines. In combination with valve actuating mechanisms of this character, a brake actuating mechanism is provided which includes a conduit 30 communicating with the main oil line, not shown. Upon a power shaft which may be the cam shaft or driven by the cam shaft, a brake cam 31 is provided, this cam being a double lobe cam for each cylinder. The cam actuates a primary brake actuating pump 33 which communicates with a conduit 34.

It will be understood, of course, that this pump or pressure source may be separate and distinct from the engine without affecting the operation of the invention. The other end of the conduit communicates with a motor chamber 35 having a piston 36 which is normally maintained in its upper position by means of a spring 37. The piston is mounted upon a rod 38 which is adapted to engage the top of head 22 as clearly shown in the drawing. A conduit 39 and an oil pressure reducing and check valve 40 provides communication between the conduit 34 and the conduit 30, while a release valve 41 and conduit 42 permits the oil pumped by the pump 33 to be returned to the engine when the brake mechanism is not in use.

A suitable link 43 causes the release valve 41 to be operated simultaneously with the rocker arm shaft shifting lever to prevent lubricant from being returned to the engine lubricating system when it is desired to operate the engine brake. The operation of the device is as fol-

lows. Under normal running conditions, the rocker arm shaft is in the down position as shown in solid lines in the drawing and the push rods actuate the inlet and exhaust valves in the usual manner. When it is no longer desired to actuate the engine, the rocker arm shaft is shifted by means of the lever 20 to lift the rocker arms and raise the tops 23 from the sockets 24, thus rendering the push rods ineffective to actuate the valve mechanism. Both the inlet and exhaust valves of the engine therefore remain closed and the braking mechanism functions to lift the exhaust valves upon the down strokes of the pistons to permit air to be drawn into the cylinders and compressed when the exhaust valves close upon the up strokes of the respective pistons. As described above, the release valve 41, being closed, causes the lubricant to be trapped within the conduit 34 and forces the piston 36 downwardly to depress shaft 38, head 22, and valve rod 14. This takes place on each exhaust valve as the respective pistons move downwardly and the engine is thus converted into an air compressor.

It will be seen that the foregoing mechanism 25 does not add to the length of the engine and utilizes the conventional valve mechanism of the engine to cause the engine to function as an air compressor and thus effect braking. No shifting cam shaft is required therefore providing a rigid 30 and noiseless drive and the parts are relatively inexpensive and simple to construct and to maintain. The engine design is not modified nor is the auxiliary equipment thereof materially changed and the braking mechanism does not constitute a 35 part of the engine which functions during normal engine operation. In view of this last condition, failure of the brake system does not impair the normal operation of the engine.

Where a multi-cylinder engine is formed of a 40 plurality of independent blocks each carrying one or more cylinders, it will be seen that the valve mechanism of the cylinders of the respective blocks may be utilized in groups or simultaneously, to effect the progressive graduation of the 45 braking effect.

It is of considerable advantage to provide a bleed valve 44 at the highest point in the fluid system, the valve being operated by stem 45 and cam 46 on the rocker arm shaft 18. When the 50 rocker arm shaft is shifted to such position that the engine functions as a brake, the bleed valve 44 is closed under the action of spring 47 and the fluid system is thus rendered tight. Upon the return of the rocker arm shaft to its normal 55 position the cam 46 opens the valve 44, as will be readily apparent from an inspection of the drawing.

While the invention has been described with specific reference to the accompanying drawing, it is not to be limited, save as defined in the appended claims.

I claim as my invention:

1. In combination with an engine having an exhaust valve and a rocker arm for actuating the valve, means to vary the position of the rocker arm to render it ineffective to actuate the valve, a pump, a motor actuated by the pump, and means to cause the motor to open the exhaust valve.
2. In combination with an engine having an exhaust valve, a rocker arm for actuating the valve, and a cam shaft for actuating the arm, means to vary the position of the axis of the arm to render it ineffective to actuate the valve, a pump driven by the cam shaft, a motor actuated

by the pump, and means actuated by the motor to open the valve.

3. In combination with an engine having an exhaust valve, a piston, a rocker arm for actuating the valve, and a cam shaft for actuating the arm, means to vary the position of the axis of the arm to render it ineffective to actuate the valve, a pump driven by the cam shaft, a motor actuated by the pump, means actuated by the motor to open the valve, and means actuated by the rocker arm varying means to open the valve upon the down stroke of the piston.

4. In combination with an engine having an exhaust valve, a rocker arm for actuating the valve, and a cam shaft for actuating the arm, means to vary the position of the axis of the arm to render it ineffective to actuate the valve, a pump driven by the cam shaft, a motor, a conduit connecting the pump and motor, a valve for relieving pressure in the conduit, a conduit communicating with a source of fluid, and a check valve in the last named conduit to prevent the flow of fluid from the pump and motor to the source.

5. In combination with an engine having an exhaust valve, a rocker arm for actuating the valve, and a cam shaft for actuating the arm, means to vary the position of the axis of the arm to render it ineffective to actuate the valve, a pump driven by the cam shaft, a motor, a conduit connecting the pump and motor, a valve for relieving pressure in the conduit, a conduit communicating with a source of fluid, a check valve in the last named conduit to prevent the flow of fluid from the pump and motor to the source, and means to actuate the relief valve from the rocker arm actuating means.

6. In combination with an engine having an exhaust valve, a rocker arm for actuating the valve, and a cam shaft for actuating the arm, means to vary the position of the axis of the arm to render it ineffective to actuate the valve, a pump driven by the cam shaft, a motor actuated by the pump having a piston rod adapted to engage the rocker arm, means to mount the motor above the valve stem, a conduit connecting the pump and motor, a valve for relieving pressure in the conduit, a conduit communicating with a source of fluid, and a check valve in the last named conduit to prevent the flow of fluid from the pump and motor to the source.

7. In combination with an engine having an exhaust valve, a rocker arm for actuating the valve, and a cam shaft for actuating the arm, means to vary the position of the axis of the arm to render it ineffective to actuate the valve, a pump driven by the cam shaft, a motor actuated by the pump having a piston rod adapted to engage the rocker arm, means to mount the motor above the valve stem, a conduit connecting the pump and motor, a valve for relieving pressure in the conduit, a conduit communicating with a source of fluid, a check valve in the last named conduit to prevent the flow of fluid from the pump and motor to the source, and means to actuate the relief valve from the rocker arm actuating means.

8. A valve mechanism for internal combustion engines permitting the engine to act as a braking means, comprising the usual valve-operating assembly including a push rod element and a connecting lever element between the push rod and the exhaust valve stem for positively opening each exhaust valve, means operating on one of said elements of each assembly for rendering the

said exhaust-valve operating assembly inoperative and means for opening each of the said exhaust valves during the down stroke of the engine piston.

5 9. A valve mechanism for internal combustion engines permitting the engine to act as a braking means, comprising the usual valve-operating assembly including a push rod and a connecting lever element between the push rod and the ex-

haust valve stem for positively opening each exhaust valve, means operating on the connecting lever element of each assembly for displacing said lever element to render the said exhaust-valve operating assembly inoperative and means for positively opening the said exhaust valve during the down stroke of the engine piston.
